UNITED STATES PATENT OFFICE.

JAMES HOBBS, OF BELLAIRE, OHIO, ASSIGNOR TO HIMSELF AND
BELMONT GLASS-WORKS, OF SAME PLACE.

DESIGN FOR GOBLETS, &c.

Specification forming part of Design No. **6,975**, dated November 4, 1873; application filed October 4, 1873.
[Term of Patent 3½ years.]

To all whom it may concern:

Be it known that I, JAMES HOBBS, of Bellaire, in the county of Belmont and State of Ohio, have invented a new and original Design for Goblet, Wine, Champagne, and Cordial Glasses; and I do hereby declare the following to be a full, clear, and exact description of the same.

The design is fully represented in the accompanying illustrative drawing, to which reference is made; and is applicable to goblets, champagne, wine, and cordial glasses.

A represents the bowl, B the stem, and C the base, of a goblet. The bowl A is flared toward the top in the usual manner; but, instead of converging by a gradual taper to the stem, has a curved bulging surface, D, that is supported upon a plate, E, which is interposed between the stem and bowl. Instead of flutings around the bowls of glasses, as usually shaped, I make the flutings a dome-shaped at top, and curved at the bottom. The stem B

consists of a head, b, foot b^1 , and connecting-pillar b^2 , all traversed by the same flutings, b^3 , which are narrowest at the middle of the pillar, and wider as they approach the head and foot, their maximum width being attained at the circumference of said head or foot.

Having thus described my invention, what I claim as new, and desire to secure by Letters Patent, is—

1. The curved surface D and supporting-plate, combined to form a new design in glasses from which liquids are to be imbibed.
2. As a new design about the bowl of glasses, the flutings a , rounded at top and bottom, as described.
3. The stem B, having the parts b b^1 b^2 , with the flutings b^3 , as a new design for the stems of glasses.

JAMES HOBBS.
